UNITED STATES PATENT OFFICE.

WILLIAM H. KELLY, OF GREENVILLE, VIRGINIA.

CONVERTIBLE SHAFTS AND POLE FOR VEHICLES.

SPECIFICATION forming part of Letters Patent No. 380,806, dated April 10, 1888.

Application filed September 7, 1887. Serial No. 249,008. (No model.)

To all whom it may concern:

Be it known that I, WILLIAM H. KELLY, a citizen of the United States of America, residing at Greenville, in the county of Augusta 5 and State of Virginia, have invented certain new and useful Improvements in Convertible Shafts and Pole for Vehicles, of which the following is a specification, reference being had therein to the accompanying drawings.

10 This invention relates to convertible shafts and pole for vehicles for use with a single horse or with two horses, as desired; and it consists in certain improvements in the construction of such devices, as hereinafter fully 15 set forth and claimed.

In the accompanying drawings, Figure 1 represents a plan view of my device, showing the shafts adjusted for use with a single horse. Fig. 2 is a plan view showing the parts adjusted to form a pole for use with two horses. Fig. 3 is a sectional plan illustrating certain 20 details. Fig. 4 is a side view of the pole. Fig. 5 is a side view of a shaft. Fig. 6 illustrates the singletree attachments. Fig. 7 is a section 25 taken on line $x-x$ of Fig. 2.

A and A' designate the cross-bars, to which are secured the rear parts, B', of the shafts, the main parts B of the shafts being detachable at a, where joints are formed, as herein- 30 stated. The ends of cross-bar A are made fast to the parts B' by means of the clips b, the sides of each part B' being reduced somewhat to receive the metal strips d, which are bolted to the rear ends of shafts B. The clips b are 35 fastened to the parts A and B', so as to leave spaces e, as seen in Fig. 3, for the strips d to be passed through, the strips being slotted at e, so that they may extend beyond the screw-bolt h and secured by means of said bolt and 40 a thumb-nut, f. The dowels g in the ends of the shafts B enter holes in the parts B when the shafts are adjusted and serve to keep the parts in line.

C indicates singletree attachments on the 45 cross-bar A, each of which has an eye, k, to receive a singletree and extends through an aperture in bar A, and is secured to a spring, i, on said bar, the spring being intended to counteract any sudden forward movement of 50 the horse. The singletrees are used when the pole adjustment for two horses is used, each

singletree being passed into an eye, k, and secured by a pin, m, passed through it. A hook, n, is formed on each eye k for attaching the traces when the shafts adjustment for a single 55 horse is used.

D indicates braces connected with the parts A and B', as shown.

E indicates a pole-piece pivotally secured to cross-bar A midway of the same, and forming 60 the rear part of the pole for use with two horses, the main part being formed of the shafts B, as hereinafter stated. This pole-piece when in position for use extends forward from bar A a suitable distance, with its rear end remov- 65 ably secured by bolt and thumb-nut to bar A'. When not in use, the piece E may be detached from bar A' and turned under and in line with bar A, so that it is out of the way. It is made of suitable size for the attachment of both the 70 shafts B, side by side, as seen in Fig. 2, the slotted strips d on each shaft extending over and under the forward part of piece E, and the dowels g entering holes in it in a manner simi- 75 lar to the attachment of shafts above described. The shafts B being detached from the parts B' and thus applied to the pole-piece are remov- 80 ably secured thereto by means of bolts and thumb-nuts p, said bolts being passed through pole-piece E and slots e in the strips d. In forming the pole the shafts B are further se- 85 cured to the pole-piece by means of a T-bolt, F, and a gripping-plate, q, through which the bolt extends, as shown. The head of the bolt is formed with points r, the plate q having simi- 90 lar points, r', and the bolt being passed through the piece E with the bolt-head cross- wise the points r enter holes in the upper iron strips, d. The plate q being then applied to the bolt at the lower side of piece E, as seen 95 in Fig. 7, the points r' of the plate enter holes in the lower strips, d, and the parts are then tightened and secured by means of a thumb- nut, s.

G indicates a detachable socket and pole 95 point, which is placed on the forward ends of the shafts B when they are brought together in forming the pole. The socket may be removably secured to the shafts in any suitable manner.

I claim as my invention--

1. In vehicle-shafts, the detachable shafts

- B, provided with slotted strips *d*, a perforated central pole-piece, E, pivotally connected with a cross-bar, and securing-bolts, substantially as set forth and described.
- 5 2. In combination with a cross-bar, A, the singletree attachments C, each provided with an eye, *k*, and a hook, *n*, substantially as and for the purposes described.
3. In combination with a cross-bar, A, the 10 singletree attachments C, each being provided with an eye, a hook, *n*, and securing-pin, and connected with a spring attached to said cross-bar, substantially as set forth and described.

4. In combination, a central pole-piece and detachable shafts of a vehicle, a bolt, F, provided with a gripping-plate, *q*, and securing-nut, substantially as and for the purposes described. 15

In testimony whereof I have affixed my signature in presence of two witnesses.

WM. H. KELLY.
